UNITED STATES PATENT OFFICE.

HENRI COANDA, OF PARIS, FRANCE.

CONSTRUCTION OF WAGONS.

1,276,621.

Specification of Letters Patent. Patented Aug. 20, 1918.

Application filed June 18, 1918. Serial No. 239,856.

To all whom it may concern:

Be it known that I, HENRI COANDA, a subject of the Kingdom of Roumania, and resident of Paris, France, have invented certain new and useful Improvements in the Construction of Wagons, of which the following is a specification.

This invention relates to an improvement in the construction of rolling stock, more especially goods wagons and above all the construction of tank wagons.

The essential characteristic of the invention consists in the feature that the frame, the platform and the body or tank which together constitute the wagon are made of reinforced concrete so as to form a monolithic structure which offers a great resistance to stresses, is easy of upkeep and is unaffected by the weather and by variations in temperature.

One embodiment of the invention is illustrated by way of example in the accompanying drawings in which Figure 1 is a side elevation and Fig. 2 an end view of a tank wagon according to the invention.

In the practice of the invention there is first erected a metallic skeleton which constitutes at once the chassis or frame adapted to be mounted on wheels, the platform and the body or tank *a* of the wagon. Hangers *b* adjoining the metallic skeleton of the tank are arranged on each side of the latter so as to constitute brackets for suspension of the wagon on the springs *c* of the wheels *d* of the vehicle.

Internally or externally of the cylindrical skeleton *a* which is to form the tank proper are arranged metallic longitudinal beams *e* which are erected with the entire skeleton structure of which they form an integral or component part and which form the longitudinals of the frame as also longitudinal ribs serving to connect all the other pieces of the metallic skeleton.

45 A dome *f* is fitted to the upper part of the wagon.

When the metallic skeleton is thus prepared, the concrete with or without centering is poured or placed thereon so as to constitute a monolithic structure of which all the parts are bound together.

Tongue attachments or other fittings for

traction apparatus, buffering, suspension, etc., are embedded in the structure.

Externally the tank is reinforced at the 55 end by one or more ribs *g* which form notched boards on which may be rested the steps of a ladder affording access to the upper part of the wagon. Internally of the wagon the said ribs *g* may be continued by longitudinal 60 partitions adapted to resist any effort tending to effect longitudinal deformation of the tank *a*.

The advantages which this system of construction of wagon presents are as follows:—

The construction is rigid and rapidly effected by a process permitting of standardization, normal and easy and inexpensive to carry out. Tank wagons thus erected are 70 upheld without difficulty and easy of repair, if any fissure should be produced by any cause. They are adapted to transport all kinds of liquids, such as wines, alcohol, petrol, etc., without the latter being influenced by variation of temperature. These wagons may be readily washed by a jet of steam or water without leaving any taste or emanation of the product previously transported.

With the object of simplifying the washing, the interior face of the wagon may be glazed by any suitable process.

The arrangements above described are to be regarded only as examples. The form, 85 dimensions, details of execution and application may vary without departure from the invention.

Having now particularly described and ascertained the nature of my said invention 90 and in what manner the same is to be performed, I declare that what I claim is:—

1. A railway tank car comprising a skeleton frame, platform and tank all formed in reinforced concrete.

2. A railway tank car comprising a tank, platform and wheel supporting brackets all formed of reinforced concrete.

3. A railway tank car comprising a tank, platform and wheel supporting brackets all 100 formed of reinforced concrete, spring connected to said brackets, and wheel supporting axles carried by said springs.

HENRI COANDA.
